UNITED STATES PATENT OFFICE

MAX POECK, OF NEW YORK, N. Y.

SANITARY CIGARETTE

Application filed August 23, 1928. Serial No. 301,511.

The main object of this invention is to provide a cigarette which prevents the nicotine content of the cigarette from entering into the mouth and nasal passages.

5 Another object of this invention is to provide a cigarette which is equipped with a pad at the drawing end to prevent the nicotine contained in the tobacco of the cigarette from passing this pad and entering the

10 mouth and nasal passages.

The above and other objects will become apparent in the description below, in which characters of reference refer to like-named parts in the drawing.

15 Referring briefly to the drawing, Figure 1 is a perspective view showing the cigarette cut in half longitudinally to illustrate the nicotine pad and holder.

Figure 2 is a partly sectioned front elevational view of the cigarette.

Figure 3 is an end elevational view of Figure 2 showing the pad holder in place in the cigarette with the pad removed.

Referring in detail to the drawing, the 25 numeral 10 indicates the cylindrical wrapper of the conventional type of cigarette. This wrapper, as stated, is cylindrical and is adapted to be filled with granulated tobacco 11. At one end of the cigarette the 30 tobacco is packed loosely in order to receive a tubular member 12 which is provided with a conical tip 13 having a plurality of perforations 14 therein. This tubular member 12 receives a pad 15 of absorbent cotton or similar other filtering material. At diametrically opposite positions the tubular member 12 is provided with raised points 16 which frictionally engage the internal wall of the 35 wrapper 10 and securely retain the pad holder, consisting of the tubular member 12 and conical roof 13, in place in one end of the cigarette. These raised points 16 stretch the material of the wrapper and securely grip the latter and thereby prevent the holder 40 from slipping out of place.

The holder may be sold as part of the cigarette or may be sold separately and be introduced into the wrapper at any desired time. In introducing the holder the tobacco 50 11, at one end of the cigarette, must be loose

and not well packed. The conical tip 13 of the holder is then pressed into the loosely packed end of the cigarette and the raised points 16 stretch the wrapper and secure this holder in place at one end of the cigarette. 55

It is to be noted that certain changes in form and construction may be made without departing from the spirit and scope of the invention.

I claim:

In a cigarette having a wrapper and a filling of tobacco, a filtering pad, a tubular holder adapted to be releasably mounted in one end of said wrapper, said pad being housed in said tubular member, a conical wall closing on one end of said tubular member, said pad resting in said conical end, said conical wall having openings therein to permit passage of smoke from one end of the cigarette through the filtering pad and 60 out of the open end of the tubular member and raised points on said tubular member for frictionally binding the wrapper to the tubular member. 65

In testimony whereof I affix my signature. 70
MAX POECK.
